UNITED STATES PATENT OFFICE.

CHARLES F. TURNER, OF BOISE, IDAHO, ASSIGNOR OF ONE-FIFTH TO EMERY WILLIAMS, ONE-FIFTH TO HARRY LE ROY, AND ONE-FIFTH TO EDWARD J. DOCKERY, ALL OF BOISE, IDAHO.

LIFT.

968,501.

Specification of Letters Patent. Patented Aug. 23, 1910.

Application filed July 28, 1909. Serial No. 510,041.

To all whom it may concern:

Be it known that I, CHARLES F. TURNER, a citizen of the United States, residing at Boise, in the county of Ada and State of Idaho, have invented new and useful Improvements in Lifts, of which the following is a specification.

The present invention is an improvement in lifts, and it resides primarily in the production of an extremely simple and powerful apparatus of the character specified, expressly designed for use in loading and unloading baggage and freight, and constructed in such a manner as to permit the articles to be loaded upon the platform of the lift and thence transferred to the car, or vice versa, without necessitating their being manually raised or lowered during such transference, thereby effecting as results an enormous saving of time and expense, and a reduction of the ordinary wear and tear upon the articles to a minimum.

The invention more particularly comprehends the application of the lifting pressure, both centrally of the platform of the lift and to the edges thereof, in contradistinction to the ordinary type of lift wherein the application of the pressure is limited to the center only of the platform. In the latter construction, experience has proven that unless the load is positioned exactly centrally of the platform, or in other words, in the line of the direction of the pressure, the platform will tilt slightly, thereby causing the piston to which it is connected to bind to a greater or less extent in the cylinder head.

The invention, therefore, resides to an extremely material extent in the employment of means for effecting the transmission of the centrally applied pressure to the edges of the platform, so as to overcome such defect.

Finally, the invention resides in the particular construction of the platform, which latter comprises relatively stationary and rotatable members, the provision of the last-mentioned member enabling the various articles of baggage or freight to be grouped thereon according to the several stations for which they are destined.

The preferred embodiment of the inven-

tion is illustrated in the accompanying drawings, wherein:

Figure 1 is a plan view of the improved lift, a portion of the upper platform member being broken away. Fig. 2 is a vertical section taken on the line 2—2 of Fig. 1. Fig. 3 is a plan view of a modified form of platform. Fig. 4 is a vertical section taken on the line 4—4 of Fig. 3.

Reference being had to said drawings, and to the characters marked thereon, A designates in a general manner the platform of the apparatus, B the hoisting mechanism connected therewith, C the station platform, and D the track.

The mechanism B is arranged within a cylindrical pit 5 located a convenient distance from the track and having a diameter substantially equal to that of platform A. This mechanism comprises essentially a piston 6, and series of levers 7 and cables 8. Piston 6 works within an upright cylinder 9 arranged centrally of the pit and mounted upon the floor thereof, its operation being controlled hydraulically by means of compressed air, steam, or other fluid admitted into the cylinder from any suitable source of supply, through a pipe 10 provided with a valve 11.

The free upper end of the piston rod 12 carries a pair of spiders 13 and 14 arranged one above the other. These spiders support, respectively, the upper and lower members 15 and 16 of platform A, the lower spider resting upon a shoulder formed upon the rod while the under face of the upper spider is provided with a bearing in which the upper terminal of the rod loosely fits.

Spider 14 has connected thereto the upper ends of the cables 8, four of which are employed in the present construction, the spider having the same number of arms. The cables are led downwardly and beneath a series of pulleys 17 mounted upon the pit floor, and thence upwardly and over pulleys 18 carried by the levers at their inner ends. Finally, the cables are again led downwardly and are secured at their ends to rings 19 secured to the pit floor. At their outer ends, the levers, which correspond in number to the cables, are connected to depending hangers 20 pivoted to the lower platform

member 16 adjacent the peripheral edge of the latter. The levers themselves are supported upon standards 21 to the upper ends of which they are pivoted, the pivots being located nearer the inner than the outer ends of the levers, as shown. This construction, as will be apparent, provides for the application of pressure against all portions of the lower platform member, the pressure applied initially to the central portion thereof being transmitted through the cables to the levers and thence to the edge portion.

The platform member in question is in the form of a skeleton framework of metallic I-beams, and is directly fastened to the lower spider, which, in turn, is fast upon the piston rod. Hence this member may be considered as stationary with respect to the apparatus as a whole. It carries upon its upper face a pair of concentrically-arranged circular tracks 22 and 23, between which and a similar pair of tracks 24 and 25 secured to the under face of the solid upper platform member are interposed series of anti-friction rollers 26 and 27, the rollers of each series being connected together by a pair of spaced annular straps 28 disposed upon opposite sides thereof and formed with perforations designed to receive the ends of the pins 29 upon which the rollers are mounted. The upper platform member is thus enabled to turn freely in either direction upon the rollers and with respect to the piston rod.

The two platform members are provided with depending peripheral guard flanges 30 and 31 which extend completely around the edges thereof, the lower guard having its upper portion offset, as indicated by the numeral 32, to provide a seat in which the lower portion of the upper guard is received, the outer faces of the guards being thus virtually flush with each other.

The hoist, as already stated, operates in connection with the station platform C, and in its normal or lowered position is flush with said platform, as shown in Figs. 2 and 4, that portion of the platform which directly overhangs the pit being cut away to provide an opening which conforms in shape and dimensions to those of the platform member 15. In its elevated position, the above-mentioned platform member is on a level with the floor of the car, (not shown). The articles of baggage or freight may thus be readily shifted from the floor of the station platform onto the lift platform, when the latter is lowered, and may be transferred from the last-mentioned platform through the car door opening, when said platform is raised, by a single movement. The guards 30 and 31 with which the lift platform is provided prevent access to the pit when said platform is raised, the mouth of the pit being closed when the plat-

form in question is in its other position. It is not essential, however, that the lift platform A be circular in shape, since a lift platform of the type shown in Figs. 3 and 4 may be made use of. The platform A' therein illustrated is rectangular in shape and its upper member consists of a relatively stationary outer section 33 and a rotatable circular inner section 34, the two sections occupying a common plane. The section 33 serves the same purpose as the station platform C, namely, to support the workman who shifts the articles of freight or baggage from the rotatable section 34 into the car, or vice versa. In this form of the invention, the lift platform is provided with a single guard 35.

Owing to the fact that the lift platform in both instances includes a rotatable section or member, it will be apparent that in case a considerable quantity of freight or baggage is to be transferred to the car and to be delivered at various stations along the route, such baggage or freight may be divided into separate groups corresponding to the several stations, the groups being arranged in the same order as the stations. When the car reaches the loading platform, the baggage master or other attendant can then transfer the groups to the car in the reverse order of the stations at which they are to be delivered. In other words, the group destined for the most remote station will be transferred first to the car and disposed at the rear end thereof; next, the group for the station nearest that station, and so on, until the group for the nearest station is reached, this group being transferred last to the car and placed nearest the door. The whole process of unloading the articles from the car will then be expedited, since there will be no occasion to hunt for the particular articles to be delivered at a station when that station is reached. Moreover, it is not necessary that an article be transferred to the station platform be placed exactly on the center of the lift platform, since the equal distribution of the pressure applied against the latter enables the same to be raised with equal facility irrespective of the position of the articles with reference thereto, and the platform when raised may be readily turned in the proper direction to bring the article in line with the car door.

The spiders 13 and 14 are carried by the piston rod, as already stated, and since the upper ends of the cables 8 which operate the levers 7 during the upward movement of the platform are directly secured to the lower spider, it is obvious that the levers may be correctly regarded as "operatively connected with" the piston. This expression is employed in the appended claims.

What is claimed is:

1. In a lift, the combination, with a platform; of a power device having means to sustain and put pressure on the platform at a fixed point; and additional devices for distributing the force of the power device evenly throughout the platform.
2. In a lift, the combination, with a platform; of means for applying pressure centrally of the platform to raise the same; and positive means for transmitting such pressure to the edge portion of the platform.
3. In a lift, the combination, with a platform; of a power device for applying pressure centrally of the platform, to raise the same; and a plurality of devices operatively connected with the power device for exerting pressure against the edge portion of the platform.
4. In a lift, the combination with a vertically-movable platform, and a motor for applying pressure centrally thereagainst; of a plurality of devices operatively connected with the motor for transmitting such pressure to the edge portion of the platform.
5. In a lift, the combination with a fluid-actuated piston, and a spider carried by the piston rod; of a platform mounted upon the spider; a series of lifting devices grouped around the piston; connections between said devices and the edge portion of the platform; and cable connections between the spider and said devices, for transmitting the energy of the piston thereto.
6. In a lift, the combination with a platform, and a hydraulic motor located beneath the center of the platform for applying pressure centrally thereagainst, to raise said platform; of a series of pivotally-mounted lifting levers grouped around the motor and located beneath the edge portion of the platform; connections between the outer ends of the levers and the edge portion of said plat-
- form; and cable connections between the inner ends of the levers and the motor.
7. In a lift, a vertically-movable platform comprising relatively fixed and movable sections arranged in the same plane.
8. In a lift, a vertically-movable platform comprising relatively fixed and rotatable sections arranged in the same plane.
9. In a lift, the combination, with a platform; of a motor capable of lifting the platform; and a series of lifting devices arranged beneath the edge portion of the platform and connected with said portion and with the motor, for control wholly by the latter during its operation.
10. In a lift, the combination, with a platform; of a motor capable of lifting the platform; and a series of pivotally-mounted lifting levers arranged beneath the edge portion of the platform and having their outer ends connected with said portion and their inner ends with the motor, for control wholly by the latter during its operation.
11. In a lift, the combination, with a platform; of a fluid-actuated piston; and a series of lifting devices arranged beneath the edge portion of the platform and connected with said portion and with the piston, for control wholly by the latter during its movements.
12. In a lift, the combination, with a platform; of a motor capable of lifting the platform; and a series of pivotally mounted lifting levers arranged beneath said platform and connected with the same and with said motor, for control wholly by the latter during its operation.

In testimony whereof I have hereunto set my hand in presence of two subscribing witnesses.
